UNITED STATES PATENT OFFICE.

WILLIAM A. MILES, OF COPAKE IRON WORKS, NEW YORK.

CHARCOAL-KILN.

SPECIFICATION forming part of Letters Patent No. 225,297, dated March 9, 1880.

Application filed October 31, 1877.

To all whom it may concern:

Be it known that I, W. A. MILES, of Copake Iron Works, county of Columbia, and State of New York, have invented a new and useful Improvement in Charcoal-Kilns; and I do hereby declare that the following is a full and exact description of the same, reference being had to the accompanying drawings, and to the letters of reference marked thereon.

10 This invention is a kiln of special construction, as will be fully described hereinafter.

In the drawings, Figure 1 represents a plan view of my improved kiln; Fig. 2, a side elevation, partially in section; and Fig. 3 a sectional elevation of a modified form of the central tube.

To enable others skilled in the art to make and use my invention, I will now proceed to fully describe the same.

20 A represents the base portion of the kiln, constructed generally of any suitable size and shape and proper material.

a represents the kiln proper, resting upon the base portion, which is constructed generally 25 of any proper shape, but preferably of the form shown in the drawings.

a', Fig. 2, represents a pit or fire-chamber formed in the base portion, and a² an ash-chamber below it, communicating with the passage- 30 way a³, having the exterior door, a⁴, as shown.

a⁵ represents an arched chamber constructed over the pit a', which is provided with a suitable number of side openings, a⁶, by means of which communication is made with the interior 35 of the kiln.

a⁷ represents a central tube extending from the top of the arched chamber a⁵ to the supply-opening a⁸ at the top of the kiln, which latter is provided with the air-tight door a⁹, as 40 shown.

a¹⁰ a¹⁰ represent openings located near the upper end of the tube, by means of which, also, communication is made with the interior of the kiln. If desired, also, a series of lower openings, decreasing in area as they approach the arched chamber, may be made in the tube, as 45 shown in Fig. 3.

B represents an annular pipe surrounding the kiln near its base, which is provided with 50 a series of branches, b, leading into the interior of the kiln, and a main, b', by means of

which the products of distillation are conveyed away to the condenser b².

C represents a return-pipe leading from the condenser, or a reservoir or pressure-fan, b³, 55 connected therewith, back to the fire-chamber a', which is provided at any proper point in its length with a meter, c, Fig. 1, for controlling and determining the amount of gas delivered to the kiln.

D represents an air-pipe, communicating at one end with any suitable blowing apparatus taking supplies from the open air, and at the other with the passage a³ of the kiln, which pipe also is provided at any proper point with 65 a meter, d, for controlling and determining the amount of air delivered to the kiln.

E represents the side door, through which the wood to be carbonized is introduced, or, if desired, that to make the initial fire.

The operation is as follows: The kiln having been filled, as usual, with wood through the side door, E, the fire is lighted in the pit a', and fresh supplies of fuel are introduced, as may be necessary, through the door a⁹ at the top of the kiln. 75 Air is supplied to the initial fire through the passage-way a³; but when sufficient heat has been obtained to evolve the gases from the wood under carbonization this passage is tightly closed. Air in proper quantities may then be 80 supplied through the pipe D.

The volatile products of distillation are conveyed away through the main to the condenser, where such portions as are condensable are thrown down and drawn off in any proper manner, the remaining portions being discharged into a gasometer or pressure-fan for delivery again to the kiln through the pipe C.

By means of the meters the flow of the gas and air currents may be accurately known and 90 controlled for the purpose of obtaining the best results from their use.

It is designed, in the employment of this kiln, to use inferior wood, unfit for making charcoal, as fuel for supplying the necessary heat, 95 this being supplied at proper intervals at the upper opening in the kiln to support combustion, while that under carbonization remains undisturbed and unburned.

By this improved method the uncondensable 100 volatile products of distillation, which are composed largely of combustible gases, are returned

to the kiln to aid in the further carbonization of the wood under treatment.

By the employment of the meters it is possible to control accurately the supplies of gas and air, and thus obtain the best results from their use.

Having thus fully described my invention, what I claim as new, and desire to obtain by Letters Patent, is—

10 The kiln described, having the central per-

forated chamber, a^5 , and tube a^7 , in combination with the main B, condenser b^2 , and gas-supply pipe and the air-pipe D, as described.

This specification signed and witnessed this 20th day of October, 1877.

WILLIAM A. MILES.
